(57) CLAIM

We claim the ornamental design for a hand-held electronic device, as shown and described.

DESCRIPTION

FIG. 1 is a front elevational view of a hand-held electronic device showing our new design;

FIG. 2 is a front elevational view of a second embodiment of FIG. 1;

FIG. 3 is a front elevational view of a third embodiment of FIG. 1; and,

FIG. 4 is a front elevational view of a fourth embodiment of FIG. 1.

The undisclosed portions of the claimed design are hereby disclaimed.
